GAME NET

Fred L. Carbonero, 1623 Kingsmere,
Rochester, Mich. 48063

Filed Nov. 20, 1974, Ser. No. 525,343

Term of patent 14 years

Int. Cl. D21—01

U.S. Cl. D34—5 VV

FIG. 1

FIG. 1 is a front elevational view of a game net, the rear elevational view being substantially identical;

FIG. 2 is a top view thereof; and

FIG. 3 is a view from the right end of the game net of FIG. 1, the view from the left end being substantially identical.

I claim:

The ornamental design for a game net, substantially as shown and described.
